United States Patent Office

CHARLES KREBS, OF SPRINGFIELD, MASSACHUSETTS.

Letters Patent No. 69,224, dated September 24, 1867.

IMPROVEMENT IN ADJUSTABLE RAILING FOR VEHICLES.

The Schedule referred to in these Letters Patent and making part of the same.

TO ALL WHOM IT MAY CONCERN:

Be it known that I, CHARLES KREBS, of Springfield, Hampden county, Commonwealth of Massachusetts, have invented a new and useful improved Railing for Carriage-Seats; and I do hereby declare that the following is a full and exact description thereof, reference being had to the accompanying drawings, and to the letters of reference marked thereon. In the drawings—

Figure 1 represents a plan view of a buggy-seat, with my railing, and

Figure 2 a side section of a part of the rail;

Figure 3 being also a sectional view of a part.

This invention consists of a railing so arranged in connection with the seat of a buggy or carriage that it can be removed and replaced at pleasure.

In the drawings, *A* is the railing, attached to the seat *B* by means of the braces *a a* and *b b*. The ones *b b* are not attached to the sides of the seat by means of a latch, as are those marked *a a*, and which are on the back, but are placed, one on each side, and have projections on their ends, *c c*, which enter sockets *d d* formed for them in the sides of the seat, so that when the ends *c c* are inserted and the railing pressed down in place and latched at the back, they are also locked at the sides. (A sectional view of these side-locks is shown in fig. 3.) The rear braces *a a* are formed with notches and projections upon the lower ends, which fit in seats made for them in the pieces *f f*, attached to the back of the seat *B*. Upon the rear of the ends of the braces *a a* are the projections *g g*, which catch behind the edge of the slots *h h*, in the pieces *f f*, and are kept up by the spring of the railing. Upon the pieces *f f* are latches *i i*, which are swung upon pivots at or near their centres, and when in the same line as the pieces *f f*, lock the braces *a a* of the railing to the seat. A section of this shown in fig. 2. The lower ends of the latches *i i* are locked in place, when shut, by their own spring acting upon notches in the pieces *f f*, from which they have to be lifted when moved aside.

In this manner I obtain a railing which can easily be removed or replaced, and as the top of the buggy is attached to the railing, the vehicle can be used with or without a top, as may be desired, with only the trouble of attaching or detaching the railing. Several kinds of tops may also be applied to the same vehicle by this means.

Now, having described my invention, what I claim as new, and desire to secure by Letters Patent, is—

An adjustable railing for the seats of vehicles, which is attached by means of the notched pieces *a a* and *b b* on the rail, and the pieces *f f*, having the latches *i i* upon the seat, the parts being arranged substantially as and for the purpose described.
